UNITED STATES PATENT OFFICE.

HENRY SOMMERFELD, OF NEW YORK, N. Y.

DESIGN FOR A CIGAR AND CIGARETTE SUPPORTER.

SPECIFICATION forming part of Design No. 34,330, dated April 2, 1901.

Application filed February 19, 1901. Serial No. 48,010. Term of patent 7 years.

To all whom it may concern:

Be it known that I, HENRY SOMMERFELD, a citizen of the United States, residing at New York, borongh of Manhattan, and State of New York, have invented and produced a new and original Design for Cigar and Cigarette Supporters, of which the following is a specification, reference being had to the accompanying drawing, which is a perspective view 10 of the same.

The leading features of my design are two crosses arranged in parallel planes side by side and two bars connecting the upper outer ends of the crosses.

15 A A' indicate the two crosses having rounded central ornaments b b', and B B' the connecting-bars, which extend from the lower edges of the ends of the upper members of the crosses, so that a widened U is seen when viewed from either end.

20

What I claim is—

The design for a cigar and cigarette supporter, as shown and described.

In testimony that I claim the foregoing as my invention I have signed my name in presence of two subserbing witnesses.

25 HENRY SOMMERFELD.
